GARMENT HANGER

Albert C. Patch, Town House, Apt. 721, Topeka, Kans.
Filed June 21, 1963, Ser. No. 289,567
2 Claims. (Cl. 223—88)

This invention relates to garment hangers and more particularly it is an object of this invention to provide a hanger versatile in its use for more effectively supporting garments of different types.

An object of this invention is to provide an upper back area support made of a single layer of material which is attached to the upper part of the hanger for the purpose of holding the upper back and neck portion of a suit coat outwardly so that the fullness that is normally present in the tailoring of a suit in order that that area does not wrinkle from lack of support as is a common problem with conventional hangers.

Still another object is to provide an upper area back support as described which is removable so that groups of such hangers can be shipped and stored in a minimum of space while lying against each other.

A further object is to provide a hanger of the lower cross bar type which further has inwardly extending arms disposed below the cross bar at outer ends thereof for the purpose of cooperation with the cross bar in retaining folded pants effectively on the hanger to eliminate the common nuisance of pants weighted with billfold, coins, keys, and the like, from slipping off of a hanger and falling on a closet floor. Although pants hangers of various clamp types have long been available, yet it is a particular object to provide adequate pants support with a hanger of much lesser cost than those and in which the pants supporting portions of the hanger operate without costly moving parts and without the frustration of the accidental separation or breakage that attends the operation of moving parts.

A further object is to provide a hanger as described on and from which pants can be rapidly placed and removed.

Yet another object is to provide a hanger having inwardly extending arms as described in which pegs are provided extending upwardly from the upper side of the cross bar and above such arms, whereby the pegs tend to engage pants portions which are folded across the cross bar in order to prevent excessive sliding of the pants whereby supported pants are prevented from coming out of the spaces between the arms and the cross bar.

Still another object is to provide pegs as described having the additional function that they are adapted to support garments and articles of various types and can, for example, be used for the reception of shoulder straps therearound it, being possible to store on the same hanger both pants and a shoulder strap garment, if desired, and in addition thereto on the same hanger, a suit coat can be supported.

Still another object is to provide a hanger as described, the inwardly extending arm portions of which have upper surfaces, the majority of the length of which are substantially straight and horizontal for the support of pants with a minimum of wrinkling, the only exception to the straightness of the upper surface of the arms being upwardly extending inner ends which are adapted to engage the pants to retain them from sliding along the cross bar of the hanger so that they do not slip out of slots above the arms.

Still another object is to provide the said inwardly extending arms with turned-up inner ends for the better hanging of dresses or garments without sleeves or wider shoulder strap garments, as these up-turned ends prevent such garments from falling off.

2

Other and further objects and advantages of the present invention will be apparent from the following detailed description, drawings and claims, the scope of the invention not being limited to the drawings themselves as the drawings are only for the purpose of illustrating a method of which the principles of this invention can be applied.

Other embodiments of the invention utilizing the same or equivalent principles may be used and structural changes may be made as desired by those skilled in the art without departing from the present invention and the purview of the appended claims.

In the drawings:

FIGURE 1 is a side elevation of the hanger of this invention, with its back support in a supporting position.

FIGURE 2 is an end view of the hanger in FIGURE 1 as seen from the left, a coat being shown thereon in dotted lines.

FIGURE 3 is a top plan view of the hanger of FIGURE 1.

FIGURE 4 is a sectional view as seen along the line 4—4 of FIGURE 1 and showing a portion of a pair of pants shown in position on the hanger.

The hanger of this invention is generally indicated at 10 and has a first or upper member generally indicated at 12 having upper surfaces 14 and 16 of oppositely inclined bilateral portions 18 and 20 respectively.

The surfaces 14 and 16 are themselves oppositely inclined with respect to each other and are inclined with respect to the vertical and the horizontal in a conventional manner. A hook 30 extends upwardly from the first member in a position centrally disposed between its ends.

The hanger has a garment back support made of a single layer of material generally indicated at 40 disposed in a use position extending outwardly from one side of the hanger as best seen in FIGURE 2. The support 40 has an outer convex surface 50 for engaging the upper back area 54 of a garment 60 shown in dotted lines in FIGURE 2 at times when the garment is disposed on the hanger.

The said back support 40 further has an attachment means fixing it to a respective side of the hanger, such attachment means being generally indicated at 70 in FIGURE 2 and preferably being formed integrally with the support 40 and has two attachment members 72 each of which are substantially U-shaped, or to be more exact, of inverted U-shape, having open under sides providing recesses 74, and each having one side 76 attached to that side of the garment support 40 which is disposed adjacent the hanger upper or first member 12. The attachment members 72 are secured to outer extremities of support 40 in spaced relationship to each other with the convex surface 50 extending outwardly and downwardly to one side of members 72, as viewed in FIGURE 2, and when support 40 is attached on upper member 12 by members 72, no portions of convex surface 50 will rise above the upper surfaces 14 and 16 of upper member 12.

The U-shaped members are disposed one on each side of the coat or garment back support 40 and the U-shaped members 72 can have their recesses 74, best described as slots or openings, extending therethrough from side to side thereof whereby each U-shaped member 72 can be detachably hooked down onto the top of respective surfaces 14 and 16 of the upper hanger member 12, the oppositely inclined bilateral portions 18 and 20 being cooperatively shaped with respect to the U-shaped members 72 so that the members 72 will snugly fit for maintaining the support member 40 in position, but can be removed by lifting them upwardly for slid-

ing off removably from the remainder of the hanger at times when the hanger is desired to be kept in flat storage.

A garment support 40 is preferably somewhat of an umbrella top shape for providing a concave under surface indicated in FIGURE 2 at 78 with an outer surface 50 which is convex, as seen in top plan view in FIGURE 3.

The oppositely inclined bilateral portions 18 and 20 can each have a notch 80 in the upper surface thereof each for receiving a strap of a garment.

The garment back support 40 is provided because most coats have a fullness immediately beneath the neck portion. The coat is indicated at 120 with a lapel or neck line 122 and shoulder indicated at 124. Those coats having a fullness beneath the neck at the back thereof tend to form a wrinkle at this portion when on conventional-type hangers which is overcome with this invention by extending the back support 40 so that the coat does not hang loosely at that back place immediately beneath the neck line.

A cross bar 130 is integrally formed with and extends horizontally between the lower ends of the bilateral portions 18 and 20 in a conventional manner. Outer ends 132 and 134 of the cross bar 130 are provided with arms 136 which are extended inwardly from the said ends at a position lower down, spaced apart and parallel to the cross bar 130. The arms 136, at their inward end, are provided with upraised bosses or upwardly extending portions 138.

Spaced inwardly from the intersections of the bilateral portions 18 and 20 and the cross bar 130, pegs or stops 142 are provided integrally formed upstanding from the upper surface of the cross bar 130 and are provided to prevent pants folded over the said cross bar from sliding from side to side.

Referring now to the cross section shown in FIGURE 4, folded pant trouser legs are shown folded over the cross bar 130 and tucked into slots, notches, or hollows 148 formed by the spacing or gap between the arms 136 and the cross bar 130. It will be seen that portions of the pants tucked into the hollows 148 will rest upon the bosses 138 in two places whereby pants are permanently retained in a position as shown in FIGURE 4.

It will be seen that the bosses 138 extend upwardly from the arms 136 by a distance for serving the function of retaining pants on the arms 136 with a minimum of indenting of the pants, whereby the pants tend to remain in shape with a minimum of wrinkling of the pants. The bosses 138 are called bosses rather than pegs to choose the word to best illustrate the function described in this paragraph.

Each boss 138 preferably has a relatively sharp corner 170 on that edge of each respective boss 138 which is adjacent the respective outer end of the cross bar 130.

The bosses 138 will be seen to each extend upwardly from its arm a distance of less than one-sixth of the length of the respective arm as defines the construction in which each boss is for the only purpose of preventing pants from sliding along the respective arm.

As shown and described this invention has provided improved means for neatly storing articles of clothing and as shown and described it is thought to be obvious that a garment hanger constructed in accordance with my invention is particularly well adapted for use, by reason of the convenience and facility with which it may be assembled and operated, and it will also be obvious that my invention can be changed and modified without departing from the principles and spirit thereof, and for this reason, I do not wish to be understood as limiting myself to the precise arrangement and formation of the several parts herein shown in carrying out my invention in practice, except as claimed. The support 40 is made of a single layer of material.

From the foregoing description, it is thought to be

obvious that a garment hanger constructed in accordance with my invention is particularly well adapted for use, by reason of the convenience and facility with which it may be assembled and operated, and it will also be obvious that my invention can be changed and modified without departing from the principles and spirit thereof, and for this reason, I do not wish to be understood as limiting myself to the precise arrangement and formation of the several parts herein shown in carrying out my invention in practice, except as claimed.

I claim:

1. A garment hanger having a first member having an upper portion having upper surfaces oppositely inclined with respect to each other and inclined with respect to the vertical in a conventional manner, said upper portion having downwardly extending forward and rearward side surfaces adjoining respective opposite sides of said inclined upper surfaces respectively, said first member having a centrally disposed hook attached thereto and extending upwardly therefrom, a garment back support disposed in use position extending outwardly from a back of the hanger, said support having an outer convex surface for engaging the upper back area of a garment disposed on said hanger, said support having an attaching means attaching the support to the upper, forward and side surfaces of said first member, said attaching means comprising two substantially U-shaped members having open under sides with said U-shaped members being attached to outer extremities of said support in spaced relation to each other with the convex surface of said support projecting outwardly and downwardly to one side of said attaching means, each substantially U-shaped member having one side attached to that side of said support which is adjacent said hanger, said U-shaped members being disposed one on each side of said hook whereby each U-shaped member can be detachably hooked onto said oppositely inclined upper surfaces of said hanger, said first member side surfaces being cooperatively shaped with respect to said U-shaped members whereby at times when said U-shaped members are hooked across the upper surfaces of said garment hanger they will engage the downwardly extending surfaces of said garment hanger for firmly holding said support in said outwardly extending position to support the back portion of a garment, no portions of said convex surface rising substantial distances beyond said inclined upper surfaces whereby an economical construction is defined.

2. The combination of claim 1 further comprising the feature of there being only one single layer of material extending across the top of the inclined upper surfaces of said first member for economy, said single layer being defined by said U-shaped members, the said U-shaped members and the said convex surface being formed of a single integral piece of material for economy.
